Des. 198,589

PAGE 2

Fig. 2

Fig. 3

FIGURE 1 is a perspective view of a stereophonic high fidelity unit showing my new design;

FIGURE 2 is a top plan view;

FIGURE 3 is a right side elevational view, the side opposite being a mirror image of the side shown; and

FIGURE 4 is a perspective view thereof, showing the two drop leaf sections of the top in lowered position and the speakers detached.

I claim:

The ornamental design for a stereophonic high fidelity unit, substantially as shown and described.
